Joseph Albert,
By H. G. Underwood
Attorney

UNITED STATES PATENT OFFICE.

JOSEPH ALBERT, OF MILWAUKEE, WISCONSIN, ASSIGNOR OF ONE-HALF TO
PETER J. KAUFMANN, OF SAME PLACE.

FOOD-CABINET.

SPECIFICATION forming part of Letters Patent No. 666,952, dated January 29, 1901.

Application filed September 13, 1900. Serial No. 29,873. (No model.)

To all whom it may concern:

Be it known that I, JOSEPH ALBERT, a citizen of the United States, and a resident of Milwaukee, in the county of Milwaukee and 5 State of Wisconsin, have invented certain new and useful Improvements in Food-Cabinets; and I do hereby declare that the following is a full, clear, and exact description thereof.

10 My invention has especial reference to cabinets placed upon the counters, bars, or tables of restaurants, cafés, bakeries, and other establishments for containing perishable articles of food; and it consists in certain peculiarities of construction and combination of parts, as will be fully set forth hereinafter 15 in connection with the accompanying drawings and subsequently claimed.

In the said drawings, Figure 1 is a central 20 transverse sectional view through a device embodying my invention, taken on line 11 of Fig. 2. Fig. 2 is a plan view of said device, partly broken away to better illustrate certain details of construction.

25 Referring to the drawings, A represents the top of a counter, bar, or table, and B the base of my said cabinet, preferably raised above said top by legs b b.

C C represent the ends of the cabinet, which 30 are formed with upper rear horizontal edges united by the upper rear horizontal board D, forward of which the said upper edges of the end boards C C taper downwardly to the height of the vertical front board E, whose 35 upper edge is correspondingly beveled, so that the cover - frame F when closed may rest closely upon the upper edges of the said end boards C C and front board E, the said cover-frame being secured by hinges d d to the de- 40 scribed upper rear board D, against the forward edge of which board D the rear edge of the back piece of the said cover-frame F abuts, as best shown in Fig. 1. This cover-frame F carries a glass panel or panels G, whereby 45 the contents of the cabinet may be exposed to the view of those in front of said counter, bar, or table.

50 Access to the rear of the cabinet is obtained by opening the door formed of the rear ver- tical board H, which is hinged to the base B of the cabinet, as shown at c c. The said

door H may incline slightly forward, so as to remain closed by gravity, if preferred, when its upper part abuts against the rear edge of the board D, or said door H may be supplied 55 with a suitable spring-bolt e or other fastening device for engagement with a block or projection f on the under side of the upper rear board D, as shown in Fig. 1. The door H is shown provided with a panel I, which 60 may be of either glass or wood, as preferred.

J represents an open-topped box which is of a similar shape to that of the cabinet, within the central rear part of which it is secured, having correspondingly-inclined sides or ends 65 and a front wall of less height than its rear wall and which may be made of sheet-tin or galvanized sheet-iron, so as to avoid rusting, the said box being designed to contain ice, and the same is provided with a drain-pipe g, 70 which passes through a suitable hole in the base B of the cabinet and leads to any convenient place of discharge.

The free front edge of the cover-frame F is provided with a ring or eye h, to which is at- 75 tached one end of a cord K, and when the cabinet is located in the desired position this cord K is passed up and over a pair of pulleys i i, secured to the ceiling of the room or any other suitable support, and thence downward, 80 and to the free end of this cord is attached a weight or counterbalance L, as shown, the latter to be within reach of the attendant behind the counter or bar and of sufficient weight to just counterbalance the weight of 85 the cover-frame and panel F G when the latter is raised by pulling on the said cord K. The said pulleys are suspended wholly above and free from contact with said cabinet and ar- 90 ranged one back of the other, the front pulley being in line with the front of the cabi- net and the rear pulley arranged in horizontal line with the front pulley, but in a vertical plane back of the rear of said cabinet.

The operation of my device will be readily 95 understood from the foregoing description of its construction, taken in connection with the accompanying drawings, without further ex- planation, and the said device will be found a very useful and convenient adjunct to all 100 establishments where perishable articles of food or luncheon are displayed to the cus-

tomers. By elevating the cabinet above the supporting-counter or other surface a circulation of air is obtained below and all around the cabinet, which aids in the preservation 5 of the food contained therein.

Having thus described my invention, what I claim as new, and desire to secure by Letters Patent, is—

1. A food-cabinet, having an upper trans-
10 verse horizontal board at the extreme rear edge thereof, in combination with a cover-
frame hinged at its rear edge to the front edge
of said upper horizontal rear board, a pair of
pulleys suspended above and free from con-
15 tact with said cabinet, and arranged one back
of the other, the front pulley being in line
with the front of the cabinet and the rear pul-
ley arranged in horizontal line with the front
pulley, but in a vertical plane back of the
20 rear of said cabinet, a cord secured to the free
front edge of the said hinged cover-frame
and thence extending upward to the front
pulley and over the same and back horizon-
tally to and over the rear pulley, and a weight
25 secured to the free end of said cord, above
and back of the rear of said cabinet.

2. A food-cabinet, comprising a case hav-
ing a base and sides or ends, and a vertical
front board, all rigidly united together, the

front being of less height than the rear of 30
said cabinet, and an upper transverse hori-
zontal board at the extreme rear edge of the
cabinet rigidly united to said sides or ends,
and the sides or ends, forward of said upper
horizontal rear board, inclined downwardly 35
to the plane of the top of the said vertical
front board, in combination with a rear door
hinged to said base, and having its upper free
edge abutting against the rear edge of said
upper horizontal rear board; a cover-frame 40
hinged at its rear edge to the front edge of
said upper horizontal rear board, and resting
on the downwardly-inclined upper edges of
the said sides or ends, and an open-topped
ice-box secured within the central rear part 45
of said cabinet, and having correspondingly-
inclined sides or ends, and a front wall of
less height than its rear wall, and a drain-pipe
leading through the base of the cabinet.

In testimony that I claim the foregoing I 50
have hereunto set my hand, at Milwaukee, in
the county of Milwaukee and State of Wis-
consin, in the presence of two witnesses.

JOSEPH ALBERT.
